UNITED STATES PATENT OFFICE.

LOUIS MARQUART, JR., OF NEW YORK, N. Y.

DESIGN FOR A CLOCK-CASE.

SPECIFICATION forming part of Design No. 37,076, dated August 9, 1904.

Application filed June 24, 1904. Serial No. 214,055. Term of patent 3½ years.

To all whom it may concern:

Be it known that I, LOUIS MARQUART, Jr., a citizen of the United States, and a resident of Greater New York, borough of Brooklyn, 5 in the county of Kings and State of New York, have invented a new, original, and ornamental Design for Clock-Cases, of which the following is a specification.

The accompanying drawing discloses an 10 elevational view of a clock-case.

What I claim as new, and desire to secure by Letters Patent, is—

The ornamental design for a clock-case, as shown.

LOUIS MARQUART, JR.
